UNITED STATES PATENT OFFICE.

LEO MONTEL, OF NEW YORK, N. Y., ASSIGNOR TO ACETYVONE MANUFACTURING COMPANY, OF NEW YORK, N. Y., AND JERSEY CITY, NEW JERSEY, A CORPORATION OF NEW JERSEY.

ACETYLENE-GAS GENERATOR.

SPECIFICATION forming part of Letters Patent No. 705,272, dated July 22, 1902.

Application filed October 5, 1900. Serial No. 32,063. (No model.)

To all whom it may concern:

Be it known that I, LEO MONTEL, a citizen of the United States, residing in the borough of Manhattan, in the city, county, and State 5 of New York, have invented certain new and useful Improvements in Acetylene-Gas Generators, of which the following is a specification, reference being had to the accompanying drawings, forming a part hereof.

10 This invention relates to acetylene-gas generators, and has for its object to improve the construction of generators of the class referred to and particularly to produce a generator of this class which shall be well adapted for use in portable lamps, such as table-lamps, bicycle-lamps, &c.

The invention is illustrated in the accompanying drawings, in order that the nature of the invention may be clearly explained, as 20 embodied in a table-lamp, and some of the features of the invention are particularly designed for use in such a lamp; but it will be understood that it is not intended to limit the invention to its application to such a lamp nor 25 to the particular construction and arrangement of parts shown and described herein.

In said drawings, Figure 1 is a vertical sectional view of the lamp chosen for illustration of the invention. Fig. 2 is a horizontal 30 section of the grate and the scratcher. Fig. 3 is a detailed view in elevation of the lifting device. Fig. 4 is a detailed view of the carbide-holder, showing the disposition of the scratcher. Fig. 5 is a partial side view of the 35 upper portion of the lamp with the outer wall broken away, showing particularly the washing device thereof. Fig. 6 is a view illustrating a modification in the construction of the generating-chamber. Figs. 7 and 8 are detail 40 sectional views showing the cock f^3 of Fig. 6 in its open and closed positions.

In the lamp shown in the drawings the body A may be of sufficient size and of suitable shape to constitute both the container, 45 which receives the main body of water, and the reservoir, into which the water may be forced when it is displaced by accumulation of gas within the generating-chamber.

Loosely supported by the body A and clos-

ing the mouth thereof is a shell B, within 50 which a tube C is secured by means of suitable diaphragms x. These diaphragms divide the intervening space to form a gas generating and collecting chamber D in the lower portion, a pressure-equalizing chamber E in 55 the upper portion, and a gas-washing chamber F between the other two chambers. The burner, which may be of any suitable character, may be applied directly to the pressure-equalizing chamber E.

The improved generator is particularly designed for using calcium carbide in sticks prepared in some such manner as set forth in Letters Patent of the United States Nos. 648,349 and 648,350, dated April 24, 1900, and 60 while some features of the invention have particular reference to the use of the carbide in such form nevertheless the invention is not restricted, as to such features as are capable of general application, to the use of carbide in 65 any particular form. In the generator represented in the drawings a container G is provided for the carbide, such container consisting of a metal shell or tube open at the top to receive the stick of carbide and adapted to 70 be inserted into the tube C when the shell B is removed from the body A. Just below the lower end of the tube G and suspended therefrom by strips or projections o is a grating g, 75 preferably composed of concentric rings, Fig. 80 2, fastened together by a bar n, and said grating being provided with teeth g' to support the stick of carbide and to hold it from rotation in the container, for a reason to be referred to hereinafter. Below said grating and 85 likewise secured by said strips or projections is a conical head g², which is slightly larger in diameter than the tube, so as to close the lower end of the tube C when the container is inserted therein and pressed upward. The head g² 90 is preferably conical, so that the lime which falls from the calcium carbide after the action of water thereon shall, when the container is raised to remove the calcium carbide from contact with the water, lodge on the conical head 95 near its periphery, and so seal the joint against the passage of moisture into the container until it is desired to have the generation of

gas renewed once more. In order that the container may be properly guided into place and held from rotation with respect to the shell B, for a reason to be stated hereinafter, 5 it may be provided with a lug g^3 to engage an offset g^4 in the wall of the tube C, and the head g^2 is provided with a projection or tongue g^5 to close the lower open end of such offset when the container is lifted to its highest position. 10 The container is also provided below the head g^2 with a collar or ring g^6 , secured by or made integral with the strips or projections o to coöperate with the lifter hereinafter described, such collar being slotted or 15 notched, as at g^7 , to prevent accidental release of the container from the tube C, as herein-after described.

For the purpose of lowering the carbid into the water, which partly fills the font or body 20 A, and of raising the carbid out of contact with the water when it is desired to discontinue the generation of gas, a lifter H, preferably consisting of a wire frame or yoke one end of which is adapted to support the container by contact with the collar or ring g^6 , while the other is hinged or pivoted at one side of the lower end of the shell B at y , and is arranged to be operated for the purpose of raising and lowering the carbid, by means external to the body A and shell B. 25 As shown in the drawings, such means comprise a rod h , which engages the lifter H through the medium, preferably, of a swinging bar or supplemental yoke h' , the opposite ends of which are pivoted in convolutions in the wire frame H. The rod h slides with a cross fit in a tube h^2 and is provided near the upper end with a pin h^3 , which slides in a vertical slot in the tube h^2 and is adapted to swing onto a shoulder h^4 , formed at one side of said slot h^3 . The swinging bar or yoke h' accommodates itself to the movement of the lifter H about its axis, and so prevents binding of the rod h within the tube. The lifter H is preferably 40 provided with inwardly-turned fingers h^5 , which will engage the notches g^7 in the ring or collar g^6 and so prevent the container G from falling out of the tube C if the shell B, with its attached parts, should be removed 45 from the body A when the lifter is not locked in its elevated position. Above the hood which forms the upper wall (in part) of the chamber F in the construction shown is mounted the lever I, which has a cam-slot i , with which the pin h^3 of the rod h is engaged. When the lever I is turned to permit the rod h to descend to its lowest position, the pin h^3 will stand in one end of the slots i , in which position the parts will be locked by the engagement with 50 pin h^3 of the tooth i' of the cam-slot. When the lever is turned to raise the rod h to its highest position, the pin h^3 will be moved over the shoulder h^4 , and the parts will then be locked in the positions which they occupy. No jolt or jar will dislodge the parts from either position in which they are locked, and the move-

ment of the parts from such position can be effected only by operation of the lever I.

The gas generated by contact of the carbid with the water rises within the chamber D 70 through the tube f, which is bent over upon itself, so that its mouth opens below the surface of the water in the washing-chamber F. The gas is thus caused to bubble through the water and is thereby washed sufficiently. 75 From the washing-chamber the gas passes through a tube e into the pressure-equalizing chamber E, and in order to cut off the supply of gas to the pressure-equalizing chamber and thence to the burner simultaneously with 80 the lifting of the carbid from contact with the water a stop-cock e' is placed in the tube e and the lever I is secured to the stem of such stop-cock, which thereby forms the pivot of the lever. When the lever is operated to lift 85 the carbid from the water, the stop-cock is simultaneously closed to prevent the passage of gas. When the lever is operated to lower the carbid into the water, the stop-cock is simultaneously opened to permit the passage 90 of gas.

When the carbid is used in the form above referred to and disclosed in said Letters Patent No. 645,905, a coating forms on the carbid after it has been wetted and then withdrawn 95 from the water, which retards the chemical action when the carbid is again introduced in the water. Means are provided for removing this coating without requiring the carbid to be withdrawn from the generator. For 100 this purpose there is provided a scratcher K, which is rotatably mounted in the head g^2 of the carbid-container, having suitable teeth k , which pass through the grated bottom of the carbid-container G into contact with the lower 105 end of the stick of carbid, the latter being held from free movement by the teeth g' , above referred to, Fig. 2. The lower end of the stem of the scratcher is provided with a slotted head k' for engagement with a plate k^2 , which 110 is secured in a vertical position on the bottom of the body A. As described above, the carbid-retainer G is held from rotation with respect to the shell B, so that by rotating the shell B after it has been placed in position 115 in the body A, the slotted head k' engaging the plate k^2 , the scratcher will be held to rotation and the carbid be rotated with respect to the scratcher. The coating above referred to is thereby loosened and falls from the 120 carbid.

A blow-off pipe L is placed within the shell B, communicating at its upper end with the chamber E and terminating at its lower end a short distance above the lower edge of the 125 shell B. Should an excess of pressure be developed within the shell B, as by an after generation of gas when the carbid has been lifted from the water and the cock e' closed, the gas will escape through the pipe L as soon as the water is forced below the lower end of said pipe and will escape from the lamp at

the burner rather than between the hood of the shell B and the mouth of body A. It is a decided advantage to have all of the gas escape from the burner, as there can then be 5 no accidental ignition at other parts of the lamp.

It is obvious that when the shell B and its attached parts are placed in the body A more or less air will be trapped in the upper part 10 of the generating-chamber, all of which must escape through the burner before the lamp can be used unless other means are provided for its escape. As shown in the drawings, the washing-chamber F is formed partly with 15 in the shell B and partly within the dome or hood by which the shell B is supported upon the body A. The water in the washing-chamber is contained in the lower portion of the chamber. Accordingly a vent f' may be 20 formed in the floor of the higher part of the washing-chamber, and to the under side of such floor is secured a flap-valve f^2 , preferably of sheet metal, to cover the vent f' . When 25 the shell B is placed in the body A, the valve permits the escape of the entrapped air through the vent f' ; but when the shell comes to its seat on the mouth of the body A the valve is pressed tightly against the vent and so prevents the escape of gas when it is generated and passes into the generating-chamber. 30 Suitable lugs b are attached to the under side of the overhang of the dome or hood of the shell B to enter notches a in the overhanging lip a' of the body A and by engagement with such lip, when the shell B is rotated partly, serve to hold the shell B firmly 35 to its seat.

In the modification shown in Fig. 6, the lower portion of the shell B, instead of being continuous, is formed in two parts, so that the generating-chamber B may be completely submerged in water. Furthermore, the space Z between the top of the generating-chamber and the bottom of the washing-chamber receives the water which is displaced by the 45 gas in the generating-chamber, so that there is less change in the height or head of the water, and consequently greater uniformity of pressure and of action. In this construction that portion of the shell B which forms the generating-chamber is secured to the upper portion by the tube h^2 and a tube d , which delivers the gas from the generating-chamber to the washing-chamber. In this construction also a cock f^3 is provided to permit the escape of the entrapped air as the shell B is being lowered into place. The stem of this cock is provided with an arm f^4 and a weight f^5 . While the shell B is above its position 50 of rest, the weight f^5 keeps the cock open, allowing the entrapped air to escape; but as the shell B reaches its position of rest the arm f^4 makes contact with a fixed part of the body and closes the cock, the weight f^5 being 55 swung slightly outward and upward. The function of this cock is the same as the function of the vent f' and valve f^2 . (Shown in

Fig. 1.) When the shell B is placed on the body A the weight f^5 is raised, thereby closing the cock while the lever f^4 checks the further 70 movement of the valve by bearing against the wall of the chamber F.

I claim as my invention—

1. In an acetylene-gas generator, the combination with the generating-chamber and the 75 carbid-container, of a lifter fork or frame pivoted on the wall of the generating-chamber, a swinging bar secured to the arms of said fork or frame, and a lifting-rod engaging said bar. 80

2. In an acetylene-gas generator, the combination with a reservoir of a generating-chamber adapted to be placed in said reservoir and having a vent to permit the escape of entrapped air, and a valve to control said 85 vent disposed between coöperating parts of the reservoir and chamber whereby it is pressed against the vent to close the same as the generating-chamber is placed within the reservoir. 90

3. In an acetylene-gas generator, the combination of a carbid-container, a scratcher for the carbid movably mounted in the container, and means secured to the body of the generator to engage said scratcher and hold 95 the same from movement, whereby the carbid may be moved with the container and with respect to the scratcher.

4. In an acetylene-gas generator, the combination of a body, a shell rotatably supported by said body, a carbid-container held by said shell, a scratcher mounted rotatably in the end of said carbid-container and means secured to the body to engage said scratcher and hold the same from rotation as the shell 100 and carbid-container are rotated. 105

5. In an acetylene-gas generator, the combination of a reservoir, a tube adapted to be supported within said reservoir, a carbid-container adapted to be placed within said tube 110 and having a cap or head to close the lower end thereof, and means to raise and lower said container.

6. In an acetylene-gas generator, the combination of a reservoir, a shell adapted to be 115 supported within said reservoir, a carbid-container within said shell and having at its lower end a ring slotted on its lower edge, and a pivoted lifter for said container having fingers to engage said slotted ring and prevent 120 accidental separation of said container from the shell.

7. In an acetylene-gas generator, the combination with a carbid-container, of a lifter to engage the same, a rod to engage said lifter 125 and having a pin, a tube slotted for the movement of said pin, and having a shoulder to engage the same as the rod is turned at the end of its movement, and means to raise and turn said rod. 130

8. In an acetylene-gas generator, the combination with a carbid-container, a lifter to engage the same, a rod engaging said lifter and having a pin, a guide for said rod, and a

- lever having a cam-slot with a locking projection to engage said pin and operate the rod, said projection engaging with the pin to prevent accidental movement of the rod.
- 5 9. In an acetylene-gas generator, the combination with a reservoir, a generating-chamber open at its bottom, a gas-receiving chamber connected with the generating-chamber through a stop-cock, and a blow-off pipe connected to the gas-receiving chamber and terminating within the generating-chamber with its end slightly above the lower edge of the
- generating-chamber, whereby gas generated after the stop-cock is closed is discharged through the blow-off pipe into the gas-receiving chamber and is prevented from escaping through the open bottom of the generating-chamber. 15
- This specification signed and witnessed this 4th day of October, A. D. 1900.
- LEO MONTEL.
